UNITED STATES PATENT OFFICE.

CHARLES SPOFFORD, OF NEW YORK, N. Y.

GRAIN-DRIER.

SPECIFICATION forming part of Letters Patent No. 231,861, dated August 31, 1880.

Application filed July 6, 1880. (Model.)

To all whom it may concern:

Be it known that I, CHARLES SPOFFORD, a citizen of the United States, and a resident of the city of New York, county and State of New York, am the inventor of certain Improvements in Grain-Driers, of which the following is a specification.

My invention relates to an improved grain-drier, consisting of a slightly inclined horizontal cylinder placed upon wheels, which wheels are located so as to revolve on pins fixed in trunnions, in combination with spirally-wound steam coiled pipes, whose sides lie close to and touch each other, placed on the interior of said cylinder and so arranged that the grain or material to be dried shall pass through the cylinder over the heated coiled pipes in such a way as to avoid clogging, and yet so that each particle of the material to be dried is caused, by the revolution of the heated cylinder, to come into contact with the heated surface or steam-pipes, thus insuring a more complete as well as a more thorough drying of each particle of the material than has hitherto been done.

Figure 1 is a sectional longitudinal view of my invention, showing the cylinder, the coiled steam-pipes, the induct and conduit steam-pipes, &c. Fig. 2 is an end view of the same, showing the inner jacket or cylinder, the steam coiled pipe left out. Fig. 3 is an end view of the device as shown in Fig. 2.

A is the frame on which the cylinder and coiled pipes are mounted, having the raised pieces B B.

C C are arms or rests, two on the outer side of each raised piece, on which the cylinder D (the outer cylinder) rests, and in which it revolves by means of the wheels d' d''. F is the space or chamber inside of said cylinder D. The interior of this cylinder D is lined, as it were, with the spirally-coiled steam-pipes E, the same being in a continuous piece to allow the transmission of steam from one end to another. At the one end of this steam-pipe is the induct steam-pipe g, which is connected to and with the coiled pipe E, and by which steam is introduced into the said pipe E, and

on the other end is a conduit-pipe, through which all steam and the water caused by the condensation of steam are carried off and not allowed to remain and cool the chamber F. The steam-pipe may be completely shut off from contact with the material to be dried by the use of another and inner cylinder or jacket, G, which, being made of thin metal, allows the heat to readily pass through and dry the grain.

The steam may be passed into the chamber, or, if used, into the coiled pipes, by means of any of the common mechanisms now in use. There may also be used a feeding apparatus, whereby the material is carried into the chamber F, and a receptacle for receiving the said material as it passes from the cylinder after having been heated. A fanning-power may be located at the feeder for the purpose of fanning or dusting the grain as it passes into the cylinder F.

It will be observed that when the inner jacket or cylinder G is not employed, as in Fig. 1, the grain or material to be dried is brought direct into contact with the grain, and as the cylinder revolves falls directly upon the steam-pipes, and in the revolution of the inclined cylinder is carried forward to the discharge.

Around the outside of the cylinder D may be placed a jacket or covering of any suitable material which will act to retain the heat in, as it is generated by the steam passing through the pipes in said cylinder, thus giving a greater drying power.

What I claim as my invention, and desire to secure by Letters Patent, is—

A grain-drier composed of the cylinder D, which is slightly inclined and horizontal, with an outer jacket or covering, in combination with the coiled steam-pipe E, coiled against the inner side of the said cylinder D, the coils touching each other, substantially as described, and for the purpose specified.

Witness my hand this 2d day of July, 1880.

CHAS. SPOFFORD.
